 2 SHEETS—SHEET 2.

UNITED STATES PATENT OFFICE.

JULES LABARTHE, OF SAN FRANCISCO, CALIFORNIA.

SMELTING-FURNACE FOR LEAD ORES AND THE LIKE.

1,356,159.

Specification of Letters Patent. Patented Oct. 19, 1920.

Application filed September 30, 1919. Serial No. 327,479.

To all whom it may concern:

Be it known that I, JULES LABARTHE, a citizen of the United States, and resident of the city and county of San Francisco, State 5 of California, have invented new and useful Improvements in Smelting-Furnaces for Lead Ores and the like, of which the following is a specification.

My invention has for its object the design 10 and arrangement of blast furnaces for the purpose of smelting metal bearing ores, such as those containing lead, frequently associated with other values, also the accessory parts and their combined use with the said 15 furnace, whereby the smelting or reducing takes place most efficiently as regards recovery of values, the time and expense involved in the process, and a minimum depreciation of the apparatus employed. An 20 other important object is that of reducing the labor involved to a minimum.

Other objects will appear from the description which follows:

In blast furnace smelting it is desirable 25 to have the charge smelt uniformly throughout the length and breadth of the furnace; and as the actual smelting or reduction takes place at some considerable distance below the surface of the charge in the shaft of the 30 furnace the result of uneven smelting is not noted by observing the surface for several hours after the smelting irregularity has commenced. This irregularity in smelting is later indicated on the surface of the charge, 35 where depressions will occur. The irregularity will now become more aggravated because the blast has less resistance in ascending the shorter column vertically below the depressions.

40 By my invention I correct this unevenness by properly placing new charges of the same or different mixtures, as of fuel, flux, or ore where required, to secure an evenness up of the surface contour. Under the old 45 method of hand feeding, irregularity was less frequent on account of the skilled labor employed and the care exercised in shoveling the various components of the charge into the furnace and placing these at the 50 proper points. Subsequently mechanical charging came into use on account of the cost and difficulty in securing skilled and careful workmen.

In mechanical charging heretofore the 55 practice has been to employ charge cars having approximately the length of the furnace,

and these cars were filled and the charge therein carefully disposed and arranged either by shoveling the components of the charge into the cars in successive predetermined even layers at some point more convenient to the ore bins and then transferring the car to a position over the top of the furnace, or the charge car of approximately the length of the furnace was in 60 some cases filled from above through a slot by distributing in layers the components of the charge by means of similar cars, or charge buggies, or apron feeders, or belt conveyers.

In practice this method has been found to be inadequate to maintain even smelting, and entirely inadequate to correct unevenness. In fact, by the addition of charges of equal consistency, equally distributed as 75 nearly as attainable by this long charge car method; any unevenness is accumulated with each successive charge addition until an aggravated condition requiring special treatment would be arrived at.

80 In my invention I employ, for the purpose of establishing and maintaining equalized smelting throughout the furnace, an independently operated compartment car, or single individual car, each compartment or 85 car to contain a charge unit and independent dumping means with said unit, having a length of less than one half the length of the furnace. These charge units are moved preferably on tracks parallel with the length 90 of the furnace to any desired point and discharged through a longitudinal slot or opening into the furnace. I also employ scale hoppers properly spaced of proper length to uniformly distribute and discharge by 95 gravity the contents of the hoppers into the car. The arrangement which I prefer is that of a series of parallel material bins which discharge through proper chutes and gates in weighing hoppers by gravity and thence again by gravity, as required by the 100 furnace, it is discharged as a component of the charge mixture into the car or compartment. The hopper and chutes are preferably proportioned, constructed and arranged 105 so that the rate of material fed into the car or compartment will result in the material loading therein in a layer of equal thickness throughout, that is, distributed in the car compartment evenly.

110 By referring to the accompanying drawings my invention will be made clear.

Figure 1 is a cross section through my furnace on the lines I, I, of Fig. 2.

Fig. 2 is a cross section of the furnace of Fig. 1 on the line II, II, the section being 5 displaced on the right hand side of the figure to show the arrangement of blast pipes, or twyvers on the section line III, III.

Fig. 3 is a detail of one of the furnace wall plates showing the water cooling 10 compartment, in section.

The furnace is of rectangular cross section having preferably a length of not less than several times the width at the twyvers, and consists of a foundation 1, and metal 15 well 2, formed in the foundation and having a lining 3, this combination forming a crucible.

The molten metal settles in the well 2 from which it rises in the siphon 4, and is 20 withdrawn at the spout 5. Resting on this foundation are the steel walls, built up in sections and bolted together, the said sections being double walled providing water circulation compartments as shown at 6, 7, 25 8, 9. Top compartments as 10 are mounted thereon, from which the flue ducts 11, 12 abstract the gases through the openings 13, 14.

A closed in top structure 15, is provided having a sliding or rolling top plate 16, 30 which I prefer to mount upon rollers 17, 18, traveling on tracks so that the top 16 may be rolled back to uncover any portion of the length of the furnace to admit of dumping a charge therethrough. The flue connections 11 and 12 are connected with suitable draft means by which the fumes and gases arising from the smelting charge are withdrawn through the openings 13 and 14, the said draft means maintaining therein a 40 negative pressure such that no fumes or gases will arise through the opening in the top of the furnace when the top plate 16 is partially or wholly removed, but, on the contrary, there will be a downdraft of small 45 degree sufficient to prevent any of the noxious fumes circulating or penetrating through the top opening. By this means the operators on the charge floor, above the furnace, are at all times protected from exposure to the gases or fumes of the smelting operations. Air blast pressure is provided through twyvers from the pipes 19, 20 as 50 through the connecting pipe and valve 21, 22, the twyvers being connected at 23. These 55 are provided with a normally closed hand-hole 24 and a normally closed down spout 25, fitted preferably with a fusible plug and also so that they may be readily cleared of obstructions by introducing a tool through 60 the opening 24 and clearing the outlet 23 of any slag or obstruction which falls through the opening 25.

Water inlet connections are provided as 65 at 26 to the various double walled furnace compartments as 6, 7, 8, it being understood

that suitable valves as 27 are preferably to be provided on all of such circulating lines. The water inlet pipes are preferably disposed at the bottom of the circulating compartments and suitable outlet connections 70 28 to withdraw the water which may be cooled and reused if desirable. Within the water compartment of the double walls, and opposite the water inlet connections as 29, I locate a diaphragm plate 30, so that the 75 cold entering water does not directly strike the inner wall plate 31, but follows first a downward dissipating course and then upward through the said compartment in the direction indicated by the arrows 32, 33. Various arrangements of water circulation and 80 connections therefor will suggest themselves to those familiar with the art.

In this inner wall plates as 31 are prevented from burning, and in practice there 85 forms against them a chilled body of slag preventing destruction of the steel plates. Any accumulation of molten slag is withdrawn from time to time through the outlet 34 and spout 35, the molten slag and matte 90 floating upon the metal contained in the compartment 2.

The weight of the charge in the furnace occasions heavy lateral strains, tending to distort the side walls, and the assembly of 95 the furnace wall sections is preferably along straight lines, which joint lines are suitably supported from lateral truss members, as 36, 37, 38, 39, which are "tied" together at suitable intervals by transverse members 40, 100 41, 42, 43, 44, 45, the last four transverse members being also employed to support the end walls as 46, 47. The lateral walls of the furnace are thus securely "tied" together longitudinally from distortion between 105 themselves and the lateral truss members 36, 37, 38, 39, are carried to and supported from the vertical building columns 48, 49, either by direct connection therewith, or as shown in the drawing, through their 110 transverse members 40, 41, 42 and 43.

The building columns and furnace are further "tied" together by the floor structure 50, on which are also carried the tracks 51, 52, and on which the charge car 53 is 115 adapted to operate. This charge car is arranged with a two plate dumping bottom 54, 55, operable to dump and restore through the shaft connection 56, lever 57, and pawl and ratchet 58. The flue ducts 11 and 12 120 are arranged with sloping bottoms 77, 78 so that flue dust deposited there automatically discharges back into the furnace through openings 59, 60, for the further recovery of any values which it may contain.

The subsequent travel of the gases and fumes is preferably through ducts having sloping bottoms as at 61, 62, 63, 64, from which accumulating flue dust is abstracted 130

as through the openings 65 and 66 respectively.

Where a battery of furnaces is employed, common blast pipe 67 may be used to supply the air pipes as 19, 20 of the individual furnaces, and a common flue duct 68, or 69 for the gases, may be connected up with the several flue ducts as 11, 12, of the individual furnace.

At 70 is shown an angle iron on which the charge, or a portion of the charge, from the charge car 53 first falls and divides laterally to cause an equalization of the charge falling therefrom, by diverting to the sides a larger portion of coarse material. This member may be supported in any well known way, as from the ends of the furnace as 15, or it may be suspended by chains. It is well known in the art and forms no part of my invention.

An imaginary charge line is shown at 71 indicating an extra rapid smelting having taken place in the lower portions of the furnace opposite the wall plates 7 and 8 of Fig. 1, and indicating the necessity for special treatment at the surface 72 in subsequent charging.

It is obvious that any charge car discharging equally a charge throughout the length of the furnace would deposit a layer as indicated by the dotted line 73, and would not in any way correct the difficulty. On the contrary, a shorter path for the gases arising along the section line II, II, compared with other vertical paths through the charge, would, due to the extra rapid reduction going on opposite the plates 7 and 8, result in an aggravated depression as shown by the imaginary line 74, by the time the charge had smelted down, at the same time the smelting in the remaining portion of the furnace will be materially reduced.

My invention obviates this aggravation.

The operation is as follows:

The furnace charge car 53 is brought from the weighing hoppers containing its suitable mixture of ore, fuel, and flux, into the position as shown in Fig. 1, and there dumped by releasing the pawl 58, the material falling over the distributing bar 70, which is constructed and arranged so that there will be a distribution of the material as shown by the line 71 of Fig. 2; however, this increment of charge will even up the surface line 71 of Fig. 1 to the line 75, thereby preventing any subsequent aggravation of the valley 72, as to the line 74.

The furnace as now charged will smelt down so that the surface line 75, 71, is evened up to the line 76 by the time the furnace is ready for another charge.

During the smelting in the furnace the water circulation keeps the inner walls 6, 7, 8, 9, sufficiently cool so that actual combus-

tion does not take place against the walls, 65 the heavy pressure of the smelting mass is resisted by the trusses 36, 37, 38, 39, 42, 43, 44, 45. A blast is introduced through the tuyers as 23 from the pipes 21, valves 22, bustle pipes 19 and 20 from the main blast pipe 67.

The molten metal, as lead, settles into the wall 2, the surface of clean metal rising in the siphon 4 and being abstracted from the spout 5, the slag and matte is withdrawn 75 from time to time from the outlet 34, 35, the cold water entering the compartments as 7 is prevented from buckling the plates at 31 by the diaphragm 30; gases and fumes are withdrawn through flue connections 11 80 and 12 by suction means not shown. The floor plate 16 is normally positioned to close the top of the furnace, but is opened sufficiently during operation to admit from time to time charges as from car 53 to be proportioned and located to correct inequalities occurring in the charge surface as 72, the increments of charge added from time to time being proportioned and positioned to correct inequalities and constantly aim at the attainment and maintenance of a theoretical charge line.

I claim:

1. An elongated reduction furnace for lead ores having an elongated opening at 95 the top substantially equal to the length of the furnace, a sliding door for said opening; tracks adjacent to said opening; means by which the fumes and gases from the furnace are vented from below the said opening in combination with a plurality of ore conveying and dumping compartments, each having length of less than one half of the furnace length, and means adapting the compartments on the track. 100 105

2. A blast furnace for smelting lead ores and the like, consisting of a plurality of double-walled metal sections, the space between the double walls constructed and adapted for fluid circulation to cool the interior walls of the furnace for the purpose of preventing heat action in contact with said walls, said furnace constructed of assembled plates of rectangular shape and also provided with a longitudinal movable cover plate for closing the top of the furnace when not charging; laterally disposed flue venting means communicating through the upper part of the side walls; a plurality of air blast inlets laterally disposed on the lower 110 portion of the lateral walls; a well below the furnace, said well having an upriser, and a spout external to the walls, and an outlet above said well for the discharge of slag and matte. 115 120 125

3. A blast furnace for smelting lead ores and the like, consisting of a plurality of double-walled metal sections, the space be-

- tween the double walls constructed and adapted for fluid circulation to cool the interior walls of the furnace for the purpose of preventing heat action in contact with 45
- 5 said walls, said furnace constructed of assembled plates of rectangular shape and also provided with a longitudinal movable cover plate for closing the top of the furnace when not charging; laterally disposed flue venting
- 10 means communicating through the upper part of the side walls; a plurality of air blast inlets laterally disposed on the lower portion of the lateral walls; a well below the furnace, said well having an upriser, and a
- 15 spout external to the walls, and an outlet above said well for the discharge of slag and matte, in combination with truss members adapted to support the line of plate joints against the pressure of the furnace charge.
- 20 4. A blast furnace for smelting lead ores and the like, consisting of a plurality of double-walled metal sections, the space between the double walls constructed and adapted for fluid circulation to cool the interior walls of the furnace for the purpose of preventing heat action in contact with 50
- 25 said walls, said furnace constructed of assembled plates of rectangular shape and also provided with a longitudinal movable cover plate for closing the top of the furnace when not charging; laterally disposed flue venting means communicating through the upper part of the side walls; a plurality of air blast inlets laterally disposed on the lower portion of the lateral walls; a well below the furnace, said well having an upriser, and a spout external to the walls, and an outlet above said well for the discharge of slag and matte, in combination with truss 55
- 30 members adapted to support the line of plate joints against the pressure of the furnace charge, the said truss members in turn supported by and from vertically disposed columns, said columns supporting the charge
- 35
- 40
- 45
- 50
- 55
- 60
- 65
- 70
- 75
- 80
- 85
- floor; and a charge floor from which increments of charge are distributed into the furnace as required.
5. In a blast furnace of rectangular section for the reduction of metal ores; a plurality of section plates provided with water circulation compartments and forming also lateral walls tapering upward to increase the cross section as the top is approached, in combination with a well below said walls within which the reduced metal is accumulated; blast means admitting a plurality of air jets at the lower portions of the lateral walls; vent means for gases and fumes from the upper portions of said lateral walls; an opening in the top of the furnace normally closable by a movable door.
6. In a blast furnace of rectangular section for the reduction of metal ores; a plurality of section plates provided with water circulation compartments and forming also lateral walls tapering upward to increase the cross section as the top is approached, in combination with a well below said walls within which the reduced metal is accumulated; blast means admitting a plurality of air jets at the lower portions of the lateral walls; vent means for gases and fumes from the upper portions of said lateral walls; an opening in the top of the furnace normally closable by a movable door; track means adapted to convey increments of charge above the said opening at any point throughout the length of the furnace, and dump means for said charge, in combination with a charge car having a charge compartment of a length less than one half of the length of the said furnace and adapted to travel upon said tracks to any longitudinal position, as and for the purpose set forth.
- In testimony whereof, I have hereunto set my hand at San Francisco, California, this 22nd day of September, 1919.
- JULES LABARTHE.
